UNITED STATES PATENT OFFICE.

WILLIAM A. CONLEY, OF NEEDHAM HEIGHTS, MASSACHUSETTS, ASSIGNOR TO CENTRAL RAILWAY SIGNAL COMPANY, OF PITTSBURGH, PENNSYLVANIA, A CORPORATION OF NEW JERSEY.

BONNET FOR THE CAPS OF RAILWAY SIGNAL-FUSEES.

1,301,655.

Specification of Letters Patent.

Patented Apr. 22, 1919.

Application filed November 6, 1918. Serial No. 261,401.

To all whom it may concern:

Be it known that I, WILLIAM A. CONLEY, citizen of United States of America, residing at Needham Heights, in the county 5 of Norfolk and State of Mass., have invented certain new and useful Improvements in Bonnets for the Caps of Railway Signal-Fusees, of which the following is a specification, reference being had therein to the 10 accompanying drawing.

This invention relates to improvements in bonnets for the caps of railway signal fusees.

This improvement pertains to the manner 15 of attaching the tape to the bonnet for breaking away the top of the bonnet and exposing the complementary igniting material for lighting the fusee.

The primary object of my present invention 20 is to so arrange and locate the tape as to save material by shortening the length of the tape as compared with the length of tape required to arrange and attach it as heretofore used.

25 Another object of my present invention is to have the free end of the tape at the top of the bonnet, instead of at its lower end as heretofore arranged.

Another object of my present invention 30 is to wholly locate the tape at the top of the bonnet with its free end also located at that part of the fusee, whereby a saving in the length of the tape is effected as compared with the ordinary way of arranging and attaching the tape to the bonnets for caps of 35 railway signal fusees.

In the accompanying drawings—

Figure 1 is a perspective view of a railway signal fusee cap, showing a bonnet attached thereto involving my present improvement.

Fig. 2 is a perspective view of a railway signal fusee cap with my improvement applied thereto, the tape being partially torn 45 away.

Fig. 3 is a perspective view of a railway signal fusee with a cap applied thereto having a bonnet embodying my present improvement, with the tape partially torn 50 away.

Fig. 4 is a perspective view of a railway signal fusee cap with my improvement applied thereto, with the tape torn away to

expose the complementary ignition material carried at the top of the cap. 55

Fig. 5 is a longitudinal sectional view of a railway signal fusee to which my improvement is applied, showing one form of cap.

Fig. 6 is a similar sectional view to that of Fig. 5, on an enlarged scale, and showing 60 another form of cap with my improvement attached thereto.

Fig. 7 is a sectional view similar to Fig. 6, showing another form of cap with my improvement applied thereto. 65

It is well-known to those skilled in the art that a railway signal fusee comprises a tubular body-portion 1, which contains the burning compound 2. One end of the body portion 1 is usually provided with a suitable 70 spike-carrying member 3, and the other or lighting end of the fusee is provided with a lighting composition 4 applied to the outside of its upper end, as shown in Figs. 5, 6 and 7. 75

It is also understood by those skilled in the art that railway signal fusees are provided with caps of various constructions. In Fig. 5, I have shown one form of cap 5, which is a paper tube, and in this form the 80 upper end of the tube is closed by a wood plug 6. In Fig. 6, the tubular portion 5 of the cap has its upper end closed by another form of wood plug 7, and in Fig. 7 the upper end of the tube 5 of the cap is closed by 85 crimping in the paper of the upper end, as shown at 8.

The form of cap used is no part of my present invention, and it may be of any desired form, but in all cases there is applied 90 to the outside of the upper end of the cap a lighting material or composition 9, which is complementary to the lighting material 4, at the upper end of the body 1, of the fusee, and these igniting materials 9 and 14 are 95 complementary, as is the head of a safety-match and the composition on the outside of the boxes containing the matches.

In fusees as used, the caps are provided with a paper bonnet which comprises a 100 piece of paper which is wrapped around the outer end of the cap and folded inward over the igniting material 9, for the purpose of protecting it. Thus far I have described what is common to fusees as now used.

My present improvement consists in ap-

plying the tape 10 to the upper end of the bonnet, folding it thereon by the folding of the bonnet over the end of the cap. This arrangement places the tape in a folded approximately zigzag position, as shown in Figs. 5, 6 and 7. The sectional views 5, 6 and 7 are exaggerations of the thickness of the tape and the folded in portion 11 of the bonnet 12, so far as the thickness of these 10 parts is concerned.

In my improvement the tape 10 has a projecting free end 13 to be grasped between the fingers of the user for pulling the tape out straight and thus tearing away the 15 folded portion 11 of the bonnet and expose the igniting material 9. In operation with the tape pulled out and the bonnet broken away to expose the igniting material 9, the cap is removed from the body of the fusee 20 and the fusee lighted by friction between the igniting compositions 4 and 9, as a safety match would be lighted by scratching it on its box.

When the tape 10 is drawn outward it has 25 a zigzag motion. That is to say, it is pulled first in one direction to break away one fold and then pulled in the opposite direction breaking away the other fold and exposing the igniting composition at its upper end.

In carrying out my improvement, the bonnet 12, preferably does not cover the whole 30 length of the cap 5, and the cap is fastened to the body of the fusee by wrapping a strip of paper 14 around the inner end of the cap 35 and the adjacent portion of the body of the fusee, as shown in Figs. 3, 5, 6 and 7.

In Fig. 5, the inner end 15 of the tape is fastened by having it extend between the wood plug 6 and the upper end of the cap 40 tube 5, the end of the tape being placed in the tube and the plug pushed and cemented therein.

In Fig. 6 the wood plug 7 is cemented in the end of the cap tube 5, and the end of the 45 tape 15^a is fastened by a staple 16 driven through the tape and into the wood plug 7. In Fig. 7 the end 15^b of the tape is fastened by a staple 17, which is drawn through the tape and through the closed end 8 of the 50 tube.

The bonnet and tape construction of fusee, as heretofore used and known to those skilled in the art, differs from my construction in several particulars. As heretofore used, the 55 bonnet is made sufficiently long in a single piece to project below the end of the tape to fasten the body of the fusee, and the tape passes across the top of the cap down its side between the bonnet and the cap and 60 continues down below the lower end of the bonnet (corresponding to the part 14), and with a projecting free end. From this it will be seen that the tape must be of a length considerably longer than the cap.

65 My arrangement differs from previous

constructions in that the tape is folded on top of the cap and is folded in with the folding of the end of the bonnet, so that when it is pulled out the end of the bonnet breaks away. This is a saving of approximately one-half in the length of the tape required and consequently the amount of material required.

Another advantage of my improvement is that in the old construction just described, 75 the bonnet and the tape are not applied to the cap until the cap is applied to the fusee. That is to say the cap and bonnet is not a finished product until it is applied to the fusee. The tape being fastened to the cap, 80 it is passed across the upper end down its side and along the side of the fusee, and a strip of paper of sufficient width to extend beyond the upper end of the cap and below the lower end of the cap and is pasted to 85 the cap, the tape and the fusee by a single operation with the lower end of the tape projecting below the lower end of the bonnet. In the old form when the tape is torn away the bonnet is broken away at one side 90 throughout its complete length across the top of the cap. This is a somewhat awkward operation, because the fusee, the cap and tape must all be held in proper positions while the bonnet is being wrapped around 95 them.

In my improved construction the bonnet proper consists of a relatively narrow strip 12, which will have its upper end projecting and the tape and bonnet are attached to the 100 cap and folded in as shown in Figs. 5, 6 and 7, thus making the cap with its tape a completed product ready to be attached to the fusee by simply wrapping a strip 14 around its lower end and the adjacent portion of 105 the fusee.

It has been found to be of great advantage to have the cap as a completed product on hand ready to be attached to the fusee instead of having it in an uncompleted condition and completed at the time it is applied to the fusee. My improvement not only provides a complete cap ready to be applied to a fusee, but it effects a very considerable saving in the amount of material required 115 for the tape as compared to the old way.

Again, in the old way it was necessary to grasp the fusee at a point below the lower end of the part 14 of the bonnet, because the tape extended to that point and had to be 120 broken away from that point outward. In my construction of fusee it can be grasped at its outer end near the point where the tape is torn away and no care or thought is necessary at what point the fusee is held by 125 one hand while the tape is being torn away with the other hand.

The cap with my improvement as with the old form, is broken away from the body of the fusee by simply twisting the cap which 130

will break the bonnet at the point 18, thus permitting it to be removed from the lighting end of the fusee.

Having thus described my invention, what 5 I claim and desire to secure by Letters Patent is:—

1. A cap for railway signal fusees having an exposed complementary igniting composition on its end, a tape extending over the 10 igniting material, a paper bonnet wrapped around the cap at its said end and extending beyond the cap end, the extended end of the bonnet and the tape folded and pasted together over the end of the cap and leaving 15 an end of the tape projecting from the bon-

net folds to be pulled for the purpose described.

2. A cap for railway signal fusees, having an exposed complementary igniting composition on its end, a paper bonnet wrapped 20 around said cap end, the bonnet projecting beyond the cap end, and folded thereover, and a tape between the folded portion of the bonnet and said igniting composition, one end of the tape passing out between the folds of 25 the bonnet and projecting therefrom at the end of the cap for the purpose described.

In testimony whereof I hereunto affix my signature.

WILLIAM A. CONLEY.
